UNITED STATES PATENT OFFICE

CAMILLE C. BLAIR, OF LOS ANGELES, CALIFORNIA

DESIGN FOR A DOLL

Application filed July 29, 1930. Serial No. 36,506. Term of patent 14 years.

To all whom it may concern:

Be it known that I, CAMILLE C. BLAIR, a citizen of the United States, and resident of the city of Los Angeles, State of California, have invented a new, original, and ornamental Design for a Doll, of which the following is a specification, reference being had to the accompanying drawing, forming a part hereof.

The doll is characterized, in part, by a ruffled, polka-dot dress which is of substantially the same shape and pattern both front and rear.

I claim:

The ornamental design for a doll substantially as shown and described.

Signed July 24, 1930, Los Angeles, California.

CAMILLE C. BLAIR.
